MELVIN B. BENSON, OF SUPERIOR, WISCONSIN.

PROPELLING AND BRAKING MEANS FOR TRAVELING CRANES AND CARRIAGES.

1,320,971.

Specification of Letters Patent.

Patented Nov. 4, 1919.

Application filed October 28, 1918. Serial No. 260,039.

To all whom it may concern:

Be it known that I, MELVIN B. BENSON, a citizen of the United States, residing at Superior, in the county of Douglas and 5 State of Wisconsin, have invented certain new and useful Improvements in Propelling and Braking Means for Traveling Cranes and Carriages, of which I do hereby declare the following to be a specification.

10 My invention relates to propelling and braking means for traveling cranes and carriages, and has for its object the provision of simple and effective means for starting and stopping the movement of traveling 15 cranes, dock travelers or carriages upon their tracks, or roadways. It consists of the constructions, combinations and arrangements of parts hereinafter described and claimed. In the drawings, Figure 1 is a fragmentary side elevation of a traveling crane, partly broken away and partly in diagram, equipped with my said invention. Fig. 2 is a diagrammatic plan view of means embodying my said invention. Fig. 3 is a side 20 elevation of a modified form of brake shoe within the scope of certain of my claims, and Fig. 4 is an end view of said modified form.

In the drawings, 1 is a railway track; 2 is the frame of a crane, partly broken away; 3, 4, 5 and 6 are trucks positioned on said tracks and upon which said frame is mounted. Said trucks and frame may be of any suitable structure. Pivotedly secured 35 near one of its ends to said frame or one of said trucks is a brake lever 7, the opposite end of which is weighted in any suitable manner, as by a weight 7^a suspended therefrom. At the pivoted end of said lever, a 40 brake shoe 8 is secured thereto in any suitable manner, which shoe is adapted in operative position, as when the weighted end of said lever is in lowered position, to bear against one of the wheels of one of said 45 trucks to prevent said wheel from turning. Connected to said lever at any suitable point is a link or connecting rod 7^b, one end of which is connected to a piston rod 9^a extending from an air or brake cylinder 9. 50 The chamber in said cylinder below the piston therein (not shown) communicates in any suitable manner or by any suitable means as by a pipe 9^b with the pressure chamber of an air compressor 10 of any suitable structure, which air compressor is 55 operated by an electric motor 11. A safety

valve 9^c is provided to limit the air pressure in pipe 9^b. Said motor is included in an electric circuit comprising said motor, the wires 12 and 13, controller 14, wires 15 and 16, and a generator 17, which generator may be carried by said frame, or be distant therefrom. Said wires 12 and 13 are tapped by the wires 12^a and 13^a which are connected to normally open contacts 12^b and 13^b of an electric cut out switch or circuit closer. Adjacent to said contacts but insulated therefrom and from each other are contacts 12^c and 13^c, which contacts 12^c and 13^c are in circuit through suitable connecting wires 12^d and 13^d with an electromagnet 18. Said contacts 12^c and 13^c are adapted to be brought into electric communication with the contacts 12^b and 13^b respectively by a contact closer of any suitable construction 75 adapted to be mechanically operated by the hereinafter described brake-beam, as will appear. Said wires 12^a and 13^a are tapped by wires 12^e and 13^e respectively which are connected to normally open contacts 12^f and 13^f adjacent to said magnet 18. 80 19 is an electric propelling motor of any suitable structure, which is geared to one of said trucks. The poles of said motor 19 are connected by wires 19^a and 19^b with normally open contacts 19^c and 19^d adjacent to said contacts 12^f and 13^f, and are adapted to be brought into electric communication with said contacts 12^f and 13^f by a circuit closer of any suitable structure adapted to 85 be operated by said magnet 18. Connected at one end to said brake beam intermediate of the ends thereof, is a link 20, which link is connected at its opposite end to a circuit closer 21 which is adapted to be operated 90 by said link, when said beam is in its operative or raised position, to establish electric communication between the contacts 12^b and 12^c and between the contacts 13^b and 13^c. 95

In operation, the current from the generator being turned on at the controller, said current first passes through the compressor motor 11 which motor operates the compressor 10, the air pressure passing to the cylinder 9 and raising the piston therein, thus 100 drawing up the free end of the brake beam and releasing the brake. The rising brake beam by means of the link 20 and attached circuit closer, closes the circuit between contacts 12^b and 12^c and between 13^b and 13^c, 110 whereupon part of the current flows through the magnet 18, which operates the adjacent

circuit closer 18^a to close the circuit through contacts 12^c and 19^c and through contacts 13^c and 19^a, whereupon part of the current flows through the wires 12^c and 13^c and 19^a 5 and 19^b and propelling motor 19. The motor 11 continues to operate the compressor to furnish air for maintaining the brake beam in its brake-retracting circuit-closing raised position. Upon the current being 10 cut off at the controller, said motor 11 stops and the air leaks from the cylinder 9 permitting the weight 7^a to draw the brake beam down, thus applying the brake, and at the same time retracting the circuit closer 15 between contacts 12^b and 12^c and between 13^b and 13^c. The magnet 18 drops the circuit closer governed thereby thus opening the circuit between said controller and motor 19 and preventing any flow of current to 20 said motor 19 until said brake beam shall have been raised again and the brake released.

If the trucks on transversely opposite sides of the vehicle are very far apart and 25 propelling power is applied to only one of them, the other may have a tendency to lag, thus producing torsional strains in the frame. To avoid this I prefer in such case to provide a propelling motor for the transversely opposite truck, as the motor 21, the poles of which may be tapped on to said wires 19^a and 19^b, or, if desired, may instead terminate in the normally open contacts 22, 23 opposed to normally open contacts 22^a, 23^a 30 respectively which latter contacts may be connected by tap wires with said wires 12 and 13. In the latter case said wires 12^a and 13^a may be tapped to provide current for an electromagnet 24 adapted to operate 35 a circuit closer to close the circuit between contacts 22 and 22^a, and 23 and 23^a. Thus the propelling motors 19 and 21 at transversely opposite sides of the vehicle will start or stop simultaneously. In similar 40 case, a brake beam, weight, shoe and brake cylinder for retracting or lifting said beam may be provided at the transversely opposite side of said vehicle from the first referred to beam; said second brake cylinder 45 being connected in any suitable manner with said air compressor, or with a similar air compressor. In like manner brake mechanism may be provided to individually govern the trucks at the opposite ends of the 50 vehicle. If desired, the shaft of the motor 19 may be extended across the vehicle and 55 geared to the opposite truck as well as to the one adjacent to said motor 19, in which case the motor 21 may be omitted.

60 In Fig. 3 is shown a modified form of brake shoe adapted to engage the track rail instead of the truck wheel. In said modified form, said shoe comprises jaws 25 and 26 connected together near their lower ends by 65 a tie-bar 27 pivoted thereto at its ends,

which bar is pivotally secured intermediate of its ends to the lower end of a post 28 depending from said frame 2. The upper ends of said jaws are connected together by toggle bars 29 and 30 pivoted thereto 70 at their outward ends and pivotally connected at their inner ends to the lower end of a link 31, the upper end of which link is pivotally secured to said brake beam at any suitable point. Where said brake beam is 75 in lowered position said jaws are adapted to straddle and grip one of the rails of said track. Upon the lifting of said beam said toggle bars draw the upper ends of said jaws together thus spreading the lower 80 ends thereof and feeding them from said rail.

While I have described certain tap wires between the controller and certain translation devices, it is obvious that other wire 85 arrangements may be made with equivalent electrical effect. It is also obvious that said construction may be modified in various details within the spirit and scope of certain of my claims.

What I claim is—

1. The combination with a movable support of a brake beam secured thereto; a source of electricity; a motor in circuit with said source; an air compressor adapted to be 95 operated by said motor; a brake cylinder connected to said compressor and containing a piston adapted to be operated by air from said compressor, said piston being connected to said brake beam and adapted to raise the 100 same; a normally open electric circuit connected to said source and including an electromagnet and normally open contacts; a circuit closer for closing said normally open contacts, said circuit closer being adapted to 105 be operated by said brake beam when said brake beam is raised or retracted; a normally open electric circuit connected to said source and comprising a propelling motor and normally open contacts; a circuit closer 110 adapted to be operated by said magnet to close said contacts of the latter circuit; a controller adapted to be manually operated to open or close the first said circuit; and a brake shoe carried by said brake beam; said 115 brake beam being adapted to move to brake operating position by gravity.

2. The combination with a vehicle, of a normally open electric circuit comprising a source of electricity, a normally open contact, a second normally open contact, and an electric motor for propelling said vehicle; a manually operatable contact closer for closing the first said normally open contact; a contact closer for closing said second normally open contact; a second normally open electric circuit comprising said source of electricity, a normally open contact and an electromagnet, said electromagnet being adapted to operate the contact closer for 125 130

closing the second normally open contact of said first circuit; a contact closer for closing the normally open contact of said second circuit; gravity actuated means for reTRACTING said contact closer for said second circuit; means for retracting said gravity actuated means whereby said gravity actuated means is caused to thrust said contact closer for said second circuit into operative position, and means adapted to be operated by said gravity actuated means to prevent the movement of said vehicle.

3. The combination with a vehicle, of an electric motor adapted to propel the same; a source of electricity, means for transmitting current from said source to said motor, said means including a normally open contact and a contact closer; an electromagnet adapted to close said contact closer; means for transmitting electric current from said source to said electromagnet, the latter said means including a normally open contact and a contact closer; gravity operated means adapted in operation to retract said second contact closer from operative position; a second electric motor; means for transmitting electric current from said source to said

second electric motor; an air compressor adapted to be operated by said second motor; compressed air operated means for retracting said gravity actuated means, said gravity actuated means being adapted when reTRACTED to thrust said second contact closer into operative position, said air compressor being adapted to supply compressed air for operating said compressed air operated means.

4. The combination with an electrically propelled vehicle, of a brake adapted to be held normally in operating position by gravity, fluid actuated means for releasing said brake in opposition to the influence of gravity thereon, electrically operated means for operating said fluid actuated means, said electrically operated means and the electric propelling mechanism of said vehicle including and being governed by a normally open contact common to both of them.

In testimony whereof, I hereunto affix my signature, in presence of two witnesses.

MELVIN B. BENSON.
